United States Patent Office.

ELI YORK, OF WINDSOR, ILLINOIS.

Letters Patent No. 62,718, dated March 5, 1867.

IMPROVEMENT IN PORTABLE FENCE.

The Schedule referred to in these Letters Patent and making part of the same.

TO ALL WHOM IT MAY CONCERN:

Be it known that I, ELI YORK, of Windsor, in the county of Shelby, and State of Illinois, have invented a new and useful Improvement in Portable Fence; and I do hereby declare that the following is a full, clear, and exact description thereof, which will enable others skilled in the art to make and use the same, reference being had to the accompanying drawings, forming part of this specification, in which—

Figure 1 is a vertical cross-section of my improved fence, taken through the line x x , fig. 2.

Figure 2 is a side view of a portion of my improved fence.

Similar letters of reference indicate like parts.

My invention has for its object to furnish an improved self-supporting portable fence, quickly and easily put up and taken down, and readily transported from place to place; and it consists, first, in an improved fence, formed by combining the posts, mud-sills, braces, boards, and connecting-bars, with each other, as herein-after more fully described; and, second, in forming the racks in combination with the fence by attaching slots or cross-bars to the braces and posts, as hereinafter more fully described.

A are the fence posts, the lower ends of which are framed into the ends of the mud-sills B, as shown in figs. 1 and 2. C are braces, the ends of which enter notches or mortises formed in the posts A and mud-sills B, and are secured in place by nails or spikes, as shown in fig. 1. The posts A and mud-sills B may be of any desired length or size, and may be set at any desired distance apart. The ends of the boards or planks D, which form the panels, should project considerably beyond the posts A, so that they may be overlapped in connecting the panels with each other, more or less, as the builder of the fence may require. E are the connecting-bars, by means of which the ends of the adjacent panels are secured to each other. These bars consist of two vertical bars, one on each side of the fence, connected together at their tops by a block of a thickness equal to that of the overlapped ends of the boards or planks that form the panels. This block fits into a notch formed in the upper edges of the top boards, as shown in dotted lines in fig. 2, and the bars E are secured in place by pins passing through holes formed through the said bars and the overlapped ends of the boards; or the bars E may be secured to each other and to the overlapped ends of the boards or planks D by a pin or key made somewhat in the form and operated in the manner of the key of an ox-bow, passing through the said bars E beneath the lower boards or planks D of the panels. This will usually be sufficient to hold the fence securely; but if desired, the builder may apply one or more similar keys through the said bars E, and through the overlapped ends of the boards or planks D. In erecting the fence, a corner is turned by attaching a vertical bar F to the side of the corner post by pins or spikes, said bar being kept at such a distance from the post as to allow the insertion of the ends of the boards of the adjacent panel by blocks or separating pieces inserted between the said bar and the post, as shown in fig. 2. The feed-racks are formed by attaching slats or cross-bars G to the braces C, as shown in figs. 1 and 2, and small stock may be kept from getting into the racks by attaching slats, H, to the braces C and posts A, as shown in fig. 1. In erecting the fence, the mud-sills and racks may all project on the same side of the fence, or some may be on one side and some on the other, as the circumstances of the case or the convenience of the builder may render advisable.

What I claim as new, and desire to secure by Letters Patent, is—

The combination of the post A, mud-sills B, braces C, planks D, connecting-bars E, and cross-bars G, substantially as described, for the purpose specified.

ELI YORK.
